CLAIM

The ornamental design for a container for half-popped popcorn, as shown and described.

DESCRIPTION

FIG. 1 is a front, top and side perspective view of the container for half-popped popcorn showing our new design in the closed condition;

FIG. 2 is a top plan view thereof;

FIG. 3 is a bottom view thereof;

FIG. 4 is a side elevational view thereof, the side opposite being a mirror image of the side shown in FIG. 4;

FIG. 5 is a rear elevational view thereof, the front being a mirror image of the rear shown in FIG. 5; and,

FIG. 6 is front exploded perspective view thereof in the open condition.

FIG. 1

FIG. 2

FIG. 3

FIG. 4
